UNITED STATES PATENT OFFICE

162,242

TRANSFER CAR

Earl W. Sensenich, Irwin, Pa., assignor to Irwin Foundry and Mine Car Company, North Huntingdon Township, Pa., a corporation of Pennsylvania

Application September 20, 1950, Serial No. 12,273

Term of patent 14 years

(Cl. D14—3)

To all whom it may concern:

Be it known that I, Earl W. Sensenich, a citizen of the United States, residing at Irwin, in the county of Westmoreland and Commonwealth of Pennsylvania, have invented a new, original, and ornamental Design for Transfer Cars, of which the following is a specification, reference being had to the accompanying drawing, forming part thereof.

Fig. 1 is a side elevational view of a transfer car showing my new design;

Fig. 2 is a top plan view of the same;

Fig. 3 is a perspective view of the front; and

Fig. 4 is a perspective view of the rear of the present design.

The characteristic features of my design reside in the portions shown by means of full lines in the drawing.

I claim:

The ornamental design for a transfer car, as shown and described.

EARL W. SENSENICH.
